UNITED STATES PATENT OFFICE.

THEODOSE BELANGER, OF WHITEHALL, NEW YORK, ASSIGNOR TO CHAMPLAIN SILK MILLS, OF WHITEHALL, NEW YORK, A CORPORATION OF NEW YORK.

SPINDLE FOR COP TUBES.

BEST AVAILABLE COPY

Application filed June 7, 1921. Serial No. 475,604.

To all whom it may concern:

Be it known that I, THEODOSE BELANGER, a citizen of the United States, residing at Whitehall, in the county of Washington and State of New York, have invented certain new and useful Improvements in Spindles for Cop Tubes, of which the following is a full, clear, and exact description, such as will enable others skilled in the art to which it appertains to make and use the same.

This invention relates to spindles and particularly to such spindles as are ordinarily employed in textile industries for winding thread.

It is an object of the invention to provide an improved spindle of the class mentioned with a simple, practical and efficient device for receiving and gripping a core or cop placed thereon for winding thread.

Another object is to provide an improved spindle of the class mentioned for automatically preparing a core or cop for gripping and holding the loose end of a thread wound on said core.

Still another object is to provide a spindle of the class mentioned of superior construction and functioning simply and advantageously to prepare a core or cop for securing the end of a thread wound thereon and at the same time holding said core firmly on the spindle and preventing relative rotation thereof.

Other objects will be in part obvious in connection with the following detail description and in part pointed out in connection therewith.

The invention accordingly consists in the features of construction, combination of elements and arrangement of parts which will be exemplified in the construction herein-after set forth, and the scope of the application of which will be indicated in the following claims.

In the accompanying drawings wherein an illustrative but preferred embodiment of the invention is disclosed,

Fig. 1 is a side elevation of a spindle constructed in accordance with this invention, certain parts being broken away for clearness of disclosure;

Fig. 2 is a fragmentary enlarged central longitudinal sectional view of the spindle;

Fig. 3 is a view similar to Fig. 2, a section

being taken at right angles to that of Fig. 2; and

Fig. 4 is a cross-sectional view on the line 4—4 of Fig. 2.

Referring to the drawing for a detailed description of the illustrated embodiment, a spindle 1, suitably constructed of metal preferably circular in cross-section decreasing in diameter toward its point, is adapted to be mounted on a support having means for rotating the same. As the support and rotating means form no part of the present invention, further disclosure of them is considered unnecessary.

Near its large or base end the spindle 1 is provided with a threaded extension 2 of reduced diameter for attachment to the supporting structure. A short distance above said threaded extension the spindle has a portion 3 of uniform diameter forming a cylindrical surface merging at 4 with the conical surface of the spindle. A short distance above said extension 2 the spindle is provided with longitudinally disposed diametral slot 5 continuing for a distance beyond the cylindrical portion into the conical surface. Intermediate the ends of this slot 80 is a transverse opening 6 extending on both sides thereof and extending through the spindle.

The slot 5 is adapted to receive a blade 7 having a cutting edge facing toward the end of the spindle. In width this blade is about equal in diameter to the cylindrical portion 3 so it extends at the cutting edge thereof slightly beyond the conical surface of the spindle to provide opposed aligned cutting edges 7^a and 7^b. A metallic shim or wedge 8 is disposed in slot 5 to assist in holding said blade in position, being reduced in width at one end so as not to interfere with the cutting edges.

A circular elongated shield 9 is provided on the spindle for housing and protecting the blade and for receiving the end of the cop. This shield has a central longitudinal aperture 10 just large enough to receive the cylindrical end of the spindle without binding unduly. The upper portion of the aperture 10 is bored slightly larger than the lower portion as indicated at 11 and the surface thereof may, if desired, be tapered slightly forming a conical inner surface with the

100

105

larger diameter toward the small end of the spindle. The shield is secured in position on the spindle by means of a pin 12 extending through opening 6 and through the aligning openings in the shield. It will be noted that the annular shoulder 13 of the shield engages the lower end of the blade 7 to support the same securely in operative position. The blade may be supported 10 against lateral movement by engagement therewith of the inner surface of the shield as shown in Fig. 2. The end portion 11 of the opening 10 of the shield lies adjacent the conical surface of the spindle providing 15 an annular space 14 slightly larger at its upper end for receiving the base of a winding cop. The walls of the shield extend slightly beyond the knife edges to protect the same from injury, and to prevent it from 20 injuring the operator.

The spindle is adapted for receiving the winding core or cop 15 which is preferably a conical tube corresponding to the conical formation of the spindle, and may be constructed of layers of fibrous material such as paper, wound one over another and cemented together to form walls sufficiently stiff and rigid to support the convolutions of silk or other threads to be wound thereon.

30 One of the purposes of the spindle construction herein described is to form automatically slits 16 in the end of a cop as the same is placed in position on the spindle as shown in Fig. 1, the purpose of such slits 35 being to receive and hold the loose end of a ball of thread wound on the cop. It will be obvious that this function is accomplished as the lower end of the cop is forced to seat 40 ing position into the annular space 10 against the cutting edges 7^a and 7^b of the knife disposed therein. The bottom of this space may be utilized to limit the entry of the cop and consequently the depth of the slits, or the depth may be regulated by con-

45 tact of the inner surface of the cop against the conical surface of the spindle. It will also be seen that the lower end of the cop is protected by the shield, and that the spaced portions of the knife blade penetrate and 50 grip the lower end of the cop at its diametrically opposed walls to prevent rotation thereof on the spindle, while accidental contact with the knife edge on the part of the operator is effectually guarded against.

55 As many changes could be made in the above construction and many apparently widely different embodiments of this invention could be made without departing from the scope thereof, it is intended that 60 all matter contained in the above description or shown in the accompanying drawings shall be interpreted as illustrative and not in a limiting sense.

65 It is also to be understood that the language used in the following claims is in-

tended to cover all of the generic and specific features of the invention herein described, and all statements of the scope of the invention which, as a matter of language, might be said to fall therebetween.

Having described my invention what I claim as new and desire to secure by Letters Patent, is:—

1. A spindle for use in winding textiles adapted to receive a cop, and means associated with said spindle for preparing said cop for gripping the end of a thread wound thereon.

75 2. A spindle for use in winding textiles provided with a shield for receiving the end of a cop, and means associated with said spindle for forming a slit in said cop for gripping the end of a thread wound thereon.

80 3. A spindle for use in winding textiles adapted to receive a cop, and a cutting device secured to said spindle for forming a slit in said cop for gripping the end of a thread wound thereon.

85 4. A spindle for use in winding textiles provided with a shield for receiving the end of a cop, and a cutting blade with an outwardly directed edge secured to said spindle for automatically slitting said cop when placed on said spindle thereby providing means to secure the loose end of a thread 90 wound thereon.

95 5. A spindle for use in winding textiles adapted to receive a cop and a blade having spaced outwardly directed cutting edges secured to said spindle for automatically slitting said cop at a plurality of places as the same is placed on the spindle to provide means for securing the loose end of the 100 thread.

105 6. A spindle for use in winding textiles adapted to receive a cop, a slot formed transversely in said spindle, a cutting blade disposed in said slot, and a shield on said spindle encompassing said blade.

110 7. A spindle having a shield secured near one extremity thereof, said shield having a portion spaced from said spindle to provide a receiving recess for the end of a cop, and means disposed in said recess for preparing said cop for gripping the loose 115 end of a thread wound thereon.

120 8. In a device of the character described, in combination, a spindle having a conical surface adapted to receive a conical cop, a shield associated with said spindle overlapping said conical surface to provide an annular space, and a cutting device disposed in said annular space.

In testimony whereof I affix my signature, in the presence of two witnesses.

THEODOSE BELANGER.
